UNITED STATES PATENT OFFICE.

WILL J. CAMERON, OF CHICAGO, ILLINOIS.

SURGICAL APPLIANCE.

Application filed October 13, 1920. Serial No. 416,732.

To all whom it may concern:

Be it known that I, WILL J. CAMERON, a citizen of the Dominion of Canada, residing at Chicago, in the county of Cook and State 5 of Illinois, have invented new and useful Improvements in Surgical Appliances, of which the following is a specification.

My invention relates to surgical appliances, and more specially to a device for use 10 in operating upon the eye, or in the ear of a patient, although the principle involved in the present structure may be readily employed in connection with instruments for divers other operations.

15 In designing the structure herein disclosed, I have provided means for magnifying the part being operated upon and at the same time illuminating the area at the point where the instrument is performing the operation. It has, therefore, been an object 20 of my invention to provide means for illuminating the area operated upon by means of an electric bulb or lamp, and arranging contiguous thereto a suitable lens the optical 25 axis passing through the location of the instrument being used. Another object is the provision of a device that is extremely simple to operate and which has its parts so arranged that they may be disposed or packed 30 in a relatively small space. A further object is the provision of a device that is simple in construction and made of a minimum of parts, and which is comparatively inexpensive to manufacture. I prefer to accomplish 35 the divers objects of my invention in substantially the manner hereinafter more fully described, and as more particularly pointed out in the claims, reference being had to the accompanying drawing, in which—

40 Figure 1 is a perspective view of my surgical appliance showing the same in use.

Figure 2 is a longitudinal side of a portion 45 of the structure shown in Figure 1, drawn to an enlarged scale.

Figure 3 is an end view of the instrument end of my appliance.

Figure 4 is a diagrammatic view showing the optical and light principles involved.

In the drawings, similar reference characters are employed to designate the same parts throughout the views, and by reference thereto, it will be observed my appli-

ance is used, preferably, in connection with a lamp of the elongated type, such as is disclosed in Letters Patent of the United States, 55 Number 1,208,743, issued to me December 19, 1916, for an incandescent electric lamp. As seen, this lamp comprises the elongated body 5 having a screw-plug 6 at one end and the opposite end is provided with a hemispherical or lenticular closure 7 behind which, and within body 5 is a miniature electric light bulb (not shown).

The appliance, preferably, comprises a sleeve 8 of spring metal of cylindrical shape 65 and having a longitudinal slit or split. The transverse inside diameter of sleeve 8 is normally slightly less than the exterior diameter of the lamp body 5 so that the former may be mounted upon the latter and retained in position frictionally. An instrument holder consisting of a suitable head 9 is mounted upon the under segment of sleeve 8 when in use, as seen in Figures 1, 2 and 3 of the drawings, and is provided with a bore 75 that is oblique to the longitudinal axis of the lamp body. The instrument for performing the operation has its shank inserted in the bore of head 9 and is retained therein by a set-screw 10 tapped transversely thereto into 80 the head. The instrument I have illustrated is what is known as an "eye spud" 11, and as shown in Figures 2 and 4 of the drawings, the operating point 12 is positioned at the point where the optical axis of the lamp 85 in lens 7 and the axis of the bore in head 9 intersect. This point of intersection is substantially in the cone of light condensed or converged by the lenticular end 7 of the lamp so that the part being operated upon 90 receives the maximum amount of illumination emitted from the lamp.

Upon the upper segment of sleeve 8, and preferably intermediate the ends thereof, I provide a pair of parallel lugs 13. Mounted between these lugs are the parallel clamping ears 14 of a circular rim frame 15 surrounding a convex lens 16. This construction permits the lens and rim frame 15 to be moved to desired positions, such, for example, as shown in full lines in Figure 2 when it is desired to magnify the parts under operation, or may be folded flat down against the surface of sleeve 8 when magnification 100

is not desired. This positioning of the lens is such that it may be adjusted to bring the optical axis of lens 16 through the operating point of the instrument and through the optical axis of the cone of light condensed by the condenser 7. In other words, the lens focuses upon the instrument point, and the part under operation and the lamp lens condenses upon the same point, so that all three axes intersect at one point.

I have herein described and shown my invention in connection with an instrument for performing surgical operations, but it will be obvious that said instrument may be in the form of a mechanical tool, and the device used in connection with mechanical work as well as surgical. Other changes will be obvious to others skilled in the art, and I desire it understood that all such changes or modifications are fully contemplated and coming within the scope of the appended claims.

What I claim is:

1. A surgical appliance comprising a suitable holder, a lamp positioned thereon the light whereof is directed along a given axis, an operating instrument carried by said holder the point whereof is positioned in the optical axis of illumination, and a magnifying lens pivotally carried by said structure and movable into a position whereby the optical axis thereof intersects the point of intersection between the instrument and the axis of illumination of the lamp.
2. An article of manufacture comprising a suitable holder, a tool carried thereby, an electric lamp the light whereof is directed along a given axis and illuminates the operating portion of the tool, and a lens pivotally co-operating with said holder and movable so that the optical axis thereof converges with the path of illumination and passes through the operating portion of the tool.
3. An article of manufacture comprising a suitable holder, a tool adjustably and removably carried thereby, an electric lamp the light whereof is directed along a given axis and illuminates the operating portion of said tool, and a lens hinged to said holder and movable to a position where the optical axis thereof converges with the path of illumination and passes through the operating portion of the tool.
4. The combination with an electric lamp having an elongated body, of a sleeve mounted upon and carried by said lamp body, an operating tool adjustably carried by said sleeve whereby the working portion of said tool is positioned in the zone of light emitted from said lamp, and a lens hinged to said sleeve and movable to a position so that the working portion of said tool is intersected by the optical axis of said lens.

5. The combination with an electric lamp having an elongated body, of a sleeve mounted upon and carried by said lamp body, an operating tool adjustably carried by said sleeve whereby the working portion of said tool is positioned in the zone of light emitted from said lamp, and a lens hinged to said sleeve and movable to a position substantially flat against said sleeve and to a position whereby the optical axis thereof intersects the working portion of said tool.

6. A surgical appliance comprising a suitably shaped holder and having co-operating therewith an operating instrument, an electric lamp and a lens, said instrument, lamp and lens being adjustable with respect to each other whereby the optical axis of said lens converges to the point at which the plane of the instrument intersects the light axis of said lamp.

7. The combination with an electric lamp having an elongated cylindrical body, of a sleeve slidably mounted on said lamp body, means for mounting an instrument oblique to the axis of said lamp body, whereby the outer portion of said instrument is positioned in the zone of the maximum light flux emitted from said lamp, and a lens carried by said sleeve whereby the illuminated portion of the instrument may be observed therethrough.

8. The combination with a surgical instrument, of means for illuminating the operating portion thereof, and a lens adjustably positioned so that the illuminated portion of the instrument may be observed therethrough free from interference of the light emanating from the source of illumination.

9. The combination with a surgical instrument, of a holder therefor having a clamping sleeve, an electric lamp engaged by said sleeve and positioned so as to illuminate the operating portion of said instrument, and a lens hinged to said sleeve and movable to a position whereby the optical axis thereof intersects with the operating point of the instrument.

10. A surgical appliance comprising a split cylindrical sleeve, an electric lamp having an elongated body upon which said sleeve is frictionally mounted, a holder carried by said sleeve, an operating instrument adjustably mounted in said holder the operating portion whereof is positioned on the axis of said lamp, a frame hinged on said sleeve opposite said holder, and a lens mounted in said frame and adapted to be positioned whereby the optical axis thereof intersects the axis of said lamp at the point of illumination of said instrument.

11. An article of manufacture comprising a member adapted to detachably receive a source of illumination the rays whereof are

condensed into an illuminating cone, said member having mounted thereon and extending therefrom an instrument holder adapted to detachably maintain an instrument with its point in the axis of the cone of illumination, and a magnifying element pivotally secured to said member and ro-

tatable in the plane common to the axis of the cone of illumination and the axis of said instrument.

Signed at Chicago, county of Cook and State of Illinois, this 25th day of September, 1920.

WILL J. CAMERON.
